UNITED STATES PATENT OFFICE.

JOHN T. STORY, OF ROCHESTER, NEW YORK.

DESIGN FOR A SHOW-CARD.

SPECIFICATION forming part of Design No. 21,047, dated September 15, 1891.

Application filed June 6, 1888. Serial No. 276,291. Term of patent 7 years.

To all whom it may concern:

Be it known that I, JOHN T. STORY, of the city of Rochester, county of Monroe, State of New York, have invented or produced a new and original Design for a Show-Card, of which 5 the following is a specification.

This design relates to show-cards printed with the representation of an open book and with supplementary leaves of smaller size 10 than the main leaves.

In the drawings, Figure 1 is a face view, and Fig. 2 an edge view, of the show-card.

The leading feature of the design is the new and original pattern which comprises the 15 printed representation of an open book with ordinary leaves a a and with supplementary leaves d d, of corresponding shape, but of smaller size, occupying the lower portion and leaving blanks at the edges.

b is the representation of the binding; f, ²⁰ the representation of the stitching; g, the representation of clasps, and e the representation of a suspending tag.

What I claim is—

The design for a show-card herein shown ²⁵ and described.

In witness whereof I have hereunto signed my name in the presence of two subscribing witnesses.

JOHN T. STORY.
